SURFACING TOOL

Frederick R. Dewey, Maywood, Calif.

Application April 8, 1946, Serial No. 660,463

3 Claims. (Cl. 29—76)

1

This invention relates to a device for refinishing seats in fluid flow control valves.

A type of such valve in extensive use comprises a body providing integrally a flat annular seat for cooperating with a closure member urged axially against the seat, and provided with a seat engaging surface formed, for example, of hard fiber.

Such seats often become cut, pitted or otherwise damaged as an incident to use of the valve so that the closure member is no longer effective to close the valve tightly, or at least is subject to injury by the damaged seat so as to require frequent renewals.

It is an object of this invention to provide a simple and inexpensive tool for resurfacing such seats; which may be employed while the valve is in place in the line; and which may be employed successfully without requiring especial skill on the part of the user.

It is another object of this invention to provide a tool wherein proper facing of the seat is assured without requiring the removal of an excessive amount of material from the seat.

It is another object of this invention to provide a tool having a novel form of universal connection for mounting the cutting head.

This invention possesses many other advantages, and has other objects which may be made more clearly apparent from a consideration of one embodiment of the invention. For this purpose there is shown a form in the drawings accompanying and forming part of the present specification. The form will now be described in detail illustrating the general principles of the invention; but it is to be understood that this detailed description is not to be taken in a limiting sense, since the scope of this invention is best defined by the appended claims.

In the drawing:

Figure 1 is an elevation showing a tool embodying the features of the invention, in use;

Fig. 2 is a section on an enlarged scale, taken as indicated by line 2—2 of Fig. 1;

Fig. 3 is a bottom view of the tool seen as looking upwardly in Fig. 2;

Fig. 4 is a cross section taken as indicated by line 4—4 of Fig. 2;

Fig. 5 is a view similar to Fig. 1 showing a modified form of the invention; and

Fig. 6 is a bottom view of the tool of Fig. 5.

Referring to Figs. 1 to 4 of the drawing, the tool is shown as comprising a head 1 having a cutting face 2 thereon, formed as by a hardened steel insert or file plate 3, resembling a short sec-

2

tion of a file, to form a filing or abrading surface. The opposite side edges of the insert, as clearly shown in Fig. 3 are slightly converging. Thus, the insert 3 may be secured to the head 1 by wedging it between the depending lips 1-a and 1-b of the head 1.

A shank or stem member 4 having a non-circular end portion 4-a serves to manipulate the head 1. For this purpose, the non-circular portion 4-a of the shank 4 may be engaged by a bit brace 5 shown in broken lines in Fig. 1, of a wrench (not shown), or even a door knob form of handle as indicated at 7 may be used.

Means 8 for locating and guiding the shank 4 is provided, comprising a cylindrical member having a bore 9 for rotatably accommodating the shank 4. The guide member 8 is detachably retained in the shank 4 as by having the bore 9 stepped as indicated at 9-a, the step 9-a being confined against a shoulder 10 on the shank 4 by a spring pressed detent 11 carried by the shank. Sufficient axial force exerted in opposite directions on the member 8 and the shank 4 will serve to depress the detent 11 and allow the guide member 8 to be slipped off the shank. Since member 8 is detachable, it may be replaced by a member of different outside diameter to fit different sizes of valves.

An important feature of the device is the universal connection provided at 12 connecting the head 1 and the shank 4, which in addition to permitting universal motion between the head 1 and the shank 4, permits ready removal and attachment of the head from and to the shank.

As shown in Figs. 2 and 4, the shank 4 is provided with a circular recess 13 into which a projection 14 on the head extends. This projection has a cross slot 14-a with an opening 14-b of reduced width. A pin 15 fixed in the shank 4 extends diametrically across the recess 13, and carries a spiral spring 16 having an inside diameter somewhat greater than the diameter of the pin 15 and an outside diameter greater than the width of the opening 14-b, but such that the spring may be accommodated in the slot 14-a.

From an inspection of Fig. 2, it will be clear that the head 1 has limited freedom to rock relative to shank 4 in the plane of the paper about the pin 15, and that due to the clearance between the spring 16 and the pin 15, and between the spring 16 and the slot 14-a, the head 1 can also rock in a plane perpendicular to the paper. Thus, universal movement between the head and the shank is permitted. Further, by exerting axial force urging the head 1 away from the shank, the

reduced opening 14-b distorts the circular cross section of the spring 16 so that the spring passes through the opening, allowing the head to be separated from the shank.

Conversely, the head may be attached to the shank by forcing the projection 14 into the recess 13 to cause the spring 16 to be compressed transversely by the opening 14-b and to pass into the slot 14-a where it expands to its normal shape.

The tool is shown in use in Fig. 1. Therein a valve body is indicated by 20 having a flat annular seat 21. The closure member, valve stem, bonnet, etc., have been removed to permit the seat 21 to be faced, it being understood that these parts are assembled on the body 20 by threading the bonnet (not shown), on the body neck 22. The neck 22 provides a circular opening which extends from the seat 21.

The outside diameter of the guide 8 is such that the guide fits loosely within the neck 22, serving to position the head 1 with respect to the seat 21. The universal connection 12 insures proper engagement of the cutting face 2 with the valve seat 21, regardless of any deviation of the shank 4 from a position truly normal to the seat. In this way removal of an excessive amount of material from the seat 21 is prevented.

A number of guides 8 may be provided to cooperate with different sized necks 22.

In the modified form of the invention shown in Figs. 5 and 6, the head 25 is joined to the shank 4 by a universal connection as in the previously described form. The head 25 comprises a circular disc 26 with the projection 27 for securing the head to the shank and an oppositely extending projection 28 with a non-circular portion 28-a adjacent the disc and a threaded outer portion 28-b.

A circular cutter 29 providing a cutting face 29-a is secured on the non-circular portion 28-a of projection 28 by a circular nut 30 threaded on the projection portion 28-b. This nut 30 has a diameter somewhat less than that of the port 31 about which the seat 21 extends and serves by engagement with the wall of the port 31 to maintain the head 25 in proper cutting position on the seat 21.

In both forms reciprocating rotary motion may be applied to the abrading member or cutter 3 or 29, by appropriate operation of the handle 6 or 17. In this way, the valve seat can be readily ground.

The inventor claims:

1. In a surfacing tool: a head member having a cutting face; a shank member for operating the head; one of said members having a socket, the other member having a projection loosely accommodated in said socket, said projection having a

transverse slot with a reduced opening at the end of the projection, a spiral spring secured to said one member extending across said socket and engaging the slot for securing the head to the shank for relative universal movement, said spring being adapted to be compressed transversely for passage through said reduced opening to permit separation of the head and the shank.

2. In a surfacing tool: a head member having a cutting face; a shank member for operating said head; one of said members having a projection, the other of said members forming a space in which said projection is loosely accommodated; said projection having a transverse slot with a reduced opening at the end of said projection; a resilient member secured to the said other member and extending across said space and engageable with said slot for securing said head to said shank for relative universal movement, said resilient member being adapted to be compressed transversely for passage through said reduced opening to permit separation of said head and said shank.

3. In a surfacing tool: a head member having a cutting face; a shank member for operating said head; and a limited universal coupling for said head member and said shank member, including means forming a transverse slot on said head member and a reduced opening at the end of said head member communicating with said slot, a pin carried by said shank member, and a resilient member surrounding said pin member, said pin and resilient member being receivable in said slot upon transverse compression of said resilient member for passage of said pin and resilient member through said reduced opening.
